LINT ROLLER AND BRUSH COMBINATION

Robert William Pekar, Florence, Mass., assignor to Pro-
Phy-Lac-Tic Brush Company, Florence, Mass., a cor-
poration of Delaware

Filed Mar. 10, 1966, Ser. No. 1,394

Term of patent 14 years

(Cl. D9—2)

FIG. 1 is a side elevational view of a lint roller and brush combination showing my new design;

FIG. 2 is a top view of the lint roller and brush combination shown in FIG. 1;

FIG. 3 is a bottom view of the lint roller and brush combination shown in FIG. 1;

FIG. 4 is an end view of the lint roller and brush combination shown in FIG. 1; and

FIG. 5 is a perspective view of the lint roller and brush combination shown in FIG. 1.

I claim:

The ornamental design for a lint roller and brush combination, as shown.
